UNITED STATES PATENT OFFICE.

GEORGE A. AMBLER, OF NEWARK, NEW JERSEY.

NAILING-MACHINE.

SPECIFICATION forming part of Letters Patent No. 586,153, dated July 13, 1897.

Application filed January 11, 1896. Serial No. 575,109. (No model.)

To all whom it may concern

Be it known that I, GEORGE A. AMBLER, a citizen of the United States, residing at Newark, in the county of Essex and State of New Jersey, have invented certain new and useful Improvements in Nailing-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in nailings-machines; and it consists in the novel arrangements and combinations of the several parts of mechanism hereinafter fully set forth, and finally embodied in the clauses of the claim.

The invention is fully illustrated in the accompanying sheets of drawings, in which—

Figure 1 is a front elevation of a nailings-machine provided with the mechanism embodying the principles of my invention. Fig. 2 is a side view of my novel form of combined feeding device and cutting mechanism, and Fig. 3 is a front view of the same. Fig. 4 is a vertical section of the combined feeding device and cutting mechanism, taken on line x in Fig. 3; and Fig. 5 is a cross-section taken on line y in Fig. 4 and looking in the direction of arrow y' . Fig. 6 is a bottom view of the feeding device. Fig. 6^a is a cross-section taken on line u u in Fig. 6. Fig. 7 is a face

view of the cutting or trimming mechanism represented in said Fig. 2, and Figs. 8 and 9 are perspective views of the different forms of gage-rollers adapted to be used in connection with the cutting mechanism. Fig. 10 is a side view of a portion of the standard of a nailings-machine and a modified form of construction of "jack" or standard on which the last and shoe to be nailed are supported.

Similar letters of reference are employed in all the above-described views to indicate corresponding parts.

In said drawings, A represents one of the well-known constructions of nailings-machines, comprising therein a suitable standard a , to which is secured a frame a' of proper shape to support the various working parts of the machine, said frame being provided

with suitable bearings a^2 and a^3 for the main shaft or spindle a^4 , provided with a loose pulley a^5 for receiving the driving-belt.

55

The several parts of the structure represented in Fig. 1, which are old, *per se*, are the wire-reel b , and the nailings device, of which b' is the driver-bar, and b^2 are parts of the mechanism for operating a device for severing the wire to form the nail.

Pivots connected with the lower portion of the standard a , as at a^6 , is a foot-lever d , having a weight d' adjustably arranged thereon, and d^2 is a rod which is operatively attached to a foot-lever d^{11} and is connected with a clutch-collar a^7 on the shaft a for operatively connecting said loose pulley a^5 with the shaft a , and thereby drive the several parts of the nailings-machine. Pivots attached, as at d^3 , to said lever d is a rod d^4 , usually called the "jack," which is held in the left hand of the operator of the machine and is provided at the top with a short post or pivot d^5 for the reception of the ordinary last on which the parts of the shoe are arranged, and can be brought directly into proper position beneath the novel form of feeding device when the soles are to be united to the upper of the boot or shoe or directly in front of the cutting-tool of the "trimming-off" mechanism to cut down the projecting edges of the sole and trim it off properly.

The construction of said feeding device is clearly illustrated in Figs. 2, 3, 4, 5, and 6, 85 and consists, essentially, of a suitable plate or block c , secured by means of screws or rivets c' (see Fig. 6) to the portion a^8 of the nailings-machine A in such a manner that the forward edge of said plate or block c is located directly behind a tubular post a^9 , which is secured in said portion a^8 in the manner substantially as illustrated in Fig. 4, and through which post the nail or wire is forced by the driver-bar b' in the usual manner. 90 Said block or plate c is cut away or grooved out, as at c^2 and c^3 , and is provided with a longitudinally-arranged hole c^4 , forming a bearing for the portion c^5 of a spindle or shaft c^6 . Said portion c^5 is preferably of a smaller diameter than the main portion of the spindle, whereby an offset or shoulder is formed, as clearly shown in Fig. 4. On the free end of said portion c^5 of the spindle c^6

is a pinion c^7 , which, with the shoulder on said spindle, retains the same in its rotative position in the hole c^4 in said plate or block c , as will be clearly evident from an inspection 5 of Fig. 4. On the opposite end of said spindle c^6 I have secured, preferably by means of a set-screw c^8 , a suitable driving-wheel c^9 , over which I pass a belt a^{10} , which in turn is arranged over a pulley a^{11} on the main driving 10 shaft or spindle a^4 of the machine A, as clearly represented in Fig. 1. In this manner the spindle c^6 rotates the pinion c^7 , as will be understood. Rotatively arranged in bearing portions c^{10} in said plate or block c 15 and in perforations or holes in a bracket f , secured by means of screws f' or in any other well-known manner to the end of the portion a^8 of the machine A, are a pair of short spindles f^2 , each of which is provided with a 20 gear-wheel f^3 , meshing with the pinion c^7 , arranged in the cut-away portion c^3 of the block c , and with suitably corrugated or serrated feed-rollers f^4 , substantially as illustrated in Fig. 6. From the arrangement of 25 said pinion c^7 and the two gear-wheels f^3 it will be evident that the short spindles and hence the feed-rollers f^4 thereon will both turn in the same direction during the operation of the machine. Thus it will be evi- 30 dent that when the shoe on the jack has the edge of the outer sole placed beneath the feed-rollers f^4 the operator can easily hold the shoe in its position on the jack while the feed-rollers f^4 slowly turn the shoe, and the 35 weight d' on the rod d forces the outer edge of the outer sole of the shoe into frictional contact with the corrugated or serrated surfaces of said feed-rolls f^4 , thereby causing the feeding operation, while the nails are 40 driven through the outer sole and into the inner sole of the shoe to unite the several parts of the shoe in the usual and well-known manner.

In lieu of the construction of jack illustrated in Fig. 1 I may use the form shown in 45 Fig. 10. In this instance the standard a of the machine A is provided with a pair of brackets a^{12} , having perforated ends, in which I arrange a rod d^6 , said rod being held in position by means of a collar d^7 , secured thereon by means of a set-screw d^8 and a coiled spring d^9 , which takes the place of the weight d' on the rod d and forces the rod d^4 , pivotally attached, as at d^{10} , upwardly in precisely the 50 same manner as has just been described. Said rod may be provided with a foot-piece d^{12} for lowering the same when necessary.

If desired, I may use in connection with the 55 several parts of the machine a cutting mechanism for trimming off the surrounding edge of the sole as it is being nailed fast. The construction of said cutting mechanism is clearly illustrated in Figs. 2, 3, 4, and 7, and consists, essentially, and as will be more 60 clearly understood from an inspection of said Fig. 7, of a suitable bracket e , having the flanges e' , provided with perforations e^2 . Said

bracket is provided with a groove e^3 , which can be fitted over a correspondingly-arranged rib or projection e^{11} on the under side of the 70 plate or block c (see Fig. 6) and then secured to said block or plate c by means of suitable bolts or screws g , which are screwed into the holes c^{12} in said plate c , as clearly shown in Fig. 2. In a bearing in the lower part of 75 said bracket e I have arranged a spindle e^4 , provided with a grooved wheel e^5 , which is driven by means of a belt h , passing over an idler a^{13} and a suitable pulley-wheel a^{14} on the main shaft a^4 of the machine, substantially as illustrated in Fig. 1, but any other suitable means for operating said wheel e^5 may be employed. As will be seen from Figs. 2, 4, and 7, on one side of said wheel e^5 is a projection e^6 , which is eccentrically arranged 85 in reference to the central axis of said spindle e^4 and has a ring e^7 loosely but operatively arranged thereon, substantially as shown. Said bracket is also provided with a forwardly-extending projection e^8 , which is grooved and 90 forms a suitable guide e^9 for the shank i' of the cutting-tool i . A plate k is secured by means of screws k' or in any other well-known manner over said guide and thereby operatively retains the shank i' of the cutting-tool 95 in said guide.

The cutting-tool i is connected with the shank i' in any well-known manner, but preferably by having its end i^2 arranged in a socket i^3 in the end of said shank i' and then fastened by means of a set-screw i^4 , as will be clearly understood. The lower end of the shank i' is adjustably secured by means of a set-screw i^5 to a collar i^6 , having a seat or projection i^7 , which fits into a hole in said 100 ring e^7 on said eccentric projection, as shown in Fig. 4. To the opposite sides of said bracket e are secured, by means of screws j or otherwise, the adjustable arms l and l' , each of which has a pivotal post or screw l^2 on its end 110 and on which are rotatively arranged certain gage-rollers l^3 , which may be formed as illustrated more particularly in Figs. 8 and 9, but they may be of any other suitable configuration, as will be evident. Said gage-rollers l^3 115 may be made of any suitable material, such as wood, metal, fiber, &c., but I prefer to use a comparatively soft material, such as rubber or the like.

When the outer surface of the outer sole is 120 brought in contact with the feed-rollers f^4 , hereinabove mentioned, said gage-rollers l^3 act as guides to the operator and prevent the sole or shoe from being arranged improperly beneath the feed-rollers, and all nails to be 125 driven into the sole will be equidistant from the surrounding edge of the sole, whereby a finished job is the result. These guides also serve the same purpose when the cutting mechanism is employed, and the rapidly-re- 130 ciprocating cutter or knife will properly trim the surrounding edge of the outer sole of the shoe, as will be clearly evident.

From the above description it will be seen

that an operative device or attachment has been constructed which can be used on nail-ing-machines of any well-known construction as a feeding device during the process of joining the soles to the upper of the shoe by means of wire nails, or it may be used solely as a trimmer for cutting down the surround-ing edge of the sole of the shoe, or it may be used as a combined feeding and trimming at-tachment in machines of this class.

In the manufacture of hand-sewed shoes my novel form of attachment, hereinabove de-scribed, can be used for tacking the outer sole to the shoe and trimming around the seat 15 of the sole, after which the shoe is ready to be finished.

I am fully aware that many changes may be made in the details of construction and the general arrangements of the several parts of 20 mechanism herein set forth without depart-ing from the scope of my invention. Hence I do not limit my invention to the exact ar-rangements and combinations of parts as herein described and illustrated.

Having thus described my invention, what I claim is—

1. In a nailing-machine, the combination, with the jack and the nailing device of the machine, of a feeding device for feeding the 30 sole of the shoe beneath said nailing device, and arms, as l and l' , having gage-rollers thereon, and said arms being slotted at their lower ends and provided with screws j , for adjustably securing an arm to each side of 35 said feeding device, substantially as and for the purposes set forth.

2. In a nailing-machine, the combination, with the jack and the nailing device of the machine, of a feeding device, comprising, a 40 plate or block c , means for attaching said plate or block to the machine, a main spindle ro-tatively arranged in connection with said block, a feed-roller, as f^4 , and a pulley-wheel c^9 on said spindle, and pulley-wheels a^5 and 45 a^{13} on the frame of the machine, for operating said spindle, substantially as and for the purposes set forth.

3. In a nailing-machine, the combination, with the jack and the nailing device of the 50 machine, of a feeding device, comprising, a plate or block c , means for attaching said plate or block to the machine, a main spindle ro-tatively connected with said block, a pinion on said spindle, a pair of spindles, as f^2 , gear-wheels on said spindles f^2 , meshing with said 55 pinion, and a feed-roller on each spindle f^2 , substantially as and for the purposes set forth.

4. In a nailing-machine, the combination, with the jack and the nailing device of the 60 machine, of a feeding device, comprising, a plate or block c , means for attaching said plate or block to the machine, a main spindle ro-tatively connected with said block, a pinion on said spindle, a pair of spindles, as f^2 , gear-wheels on said spindles f^2 , meshing with said 65 pinion, a feed-roller on each spindle f^2 , and

a pulley-wheel c^9 on said main spindle, sub-stantially as and for the purposes set forth.

5. The herein-described feeding device, comprising therein, a plate or block c , a main 70 spindle rotatively connected with said block, a pinion on said spindle, a pair of spindles, as f^2 , gear-wheels on said spindles f^2 , mesh-ing with said pinion, and a feed-roller on each spindle f^2 , substantially as and for the pur-75 poses set forth.

6. The herein-described feeding device, comprising therein, a plate or block c , a main 80 spindle rotatively connected with said block, a pinion on said spindle, a pair of spindles, as f^2 , gear-wheels on said spindles f^2 , mesh-ing with said pinion, a feed-roller on each spindle f^2 , and a pulley-wheel c^9 on said main spindle, substantially as and for the purposes set forth. 85

7. In a nailing-machine, the combination, with the operating mechanism of the machine, of a cutting device for trimming the edge of the sole of the shoe, comprising therein, a bracket e , a spindle e^4 , a wheel e^5 on said spin-dle, a guide in said bracket, a reciprocally-moving cutter in said guide, and means for adjustably connecting said cutter with said wheel, consisting, essentially, of an eccentric 90 connected with said wheel, and a collar and set-screw connecting the one end of said cutter with said eccentric, substantially as and for the purposes set forth.

8. The herein-described cutter mechanism, comprising therein, a bracket e , a spindle e^4 , 100 a wheel e^5 on said spindle, a guide in said bracket, a reciprocally-moving shank in said guide, a cutter connected with said shank and means for connecting said shank with said wheel, consisting essentially, of an eccentric 105 connected with said wheel, and a collar and set-screw connecting the one end of said shank with said eccentric, substantially as and for the purposes set forth.

9. The herein-described cutter mechanism, 110 comprising therein, a bracket e , a spindle e^4 , a wheel e^5 on said spindle, a guide in said bracket, a reciprocally-moving shank in said guide, a cutter connected with said shank, and means for connecting said shank with 115 said wheel, consisting, essentially, of an ec-centric connected with said wheel, and a col-lar and set-screw connecting the one end of said shank with said eccentric, and a pair of 120 arms l and l' , on said bracket having gage-rollers, substantially as and for the purposes set forth.

10. The herein-described cutter mechanism, comprising therein, a bracket e , a spin-dle e^4 , a wheel e^5 on said spindle, a guide in 125 said bracket, a reciprocally-moving shank in said guide, a cutter connected with said shank, and means for connecting said shank with said wheel, consisting, essentially, of an eccentric connected with said wheel, and a 130 collar and set-screw connecting the one end of said shank with said eccentric, and a pair

of arms l and l' on said bracket and having gage-rollers, substantially as and for the purposes set forth.

11. In a combined feeding device and trimming mechanism for nailing-machines, in combination, a plate or block c , a main spindle rotatively connected with said block, a pair of spindles f^2 , a feed-roller on each spindle f^2 , means for operating said spindles f^2 from said main spindle, a bracket e attached to said block c , a spindle e^4 , a wheel e^5 on said spindle, a guide on said bracket, a reciprocally-moving cutter in said guide, and means connecting said cutter with said wheel e^5 , consisting, essentially, of an eccentric connected with said wheel, and a collar and set-screw, connecting the one end of said cutter with said eccentric, substantially as and for the purposes set forth.
12. In a combined feeding device and trimming mechanism for nailing-machines, in combination, a plate or block c , a main spindle rotatively connected with said block, a pinion on said spindle, a pair of spindles f^2 , gear-wheels on said spindles f^2 , a bracket e attached to said block c , a spindle e^4 , a wheel e^5 on said spindle, a guide on said bracket, a

reciprocally-moving cutter in said guide, and means for connecting said cutter with said wheel e^5 , substantially as and for the purposes set forth. 30

13. In a combined feeding device and trimming mechanism for nailing-machines, in combination, a plate or block c , a main spindle rotatively connected with said block, a 35 pinion on said spindle, a pair of spindles f^2 , gear-wheels on said spindles f^2 , a bracket e attached to said block c , a spindle e^4 , a wheel e^5 on said spindle, a guide on said bracket, a reciprocally-moving cutter in said guide, and 40 means for connecting said cutter with said wheel e^5 , consisting, essentially, of an eccentric connected with said wheel, and a collar and set-screw connecting the one end of said cutter with said eccentric, substantially as 45 and for the purposes set forth.

In testimony that I claim the invention set forth above I have hereunto set my hand this 8th day of January, 1896.

GEO. A. AMBLER.
